Inventor;

Alvah Sweetland

United States Patent Office.

ALVAH SWEETLAND, OF SYRACUSE, NEW YORK, ASSIGNOR TO HIMSELF
AND MILTON J. PALMER, OF SAME PLACE.

Letters Patent No. 75,074, dated March 3, 1868.

IMPROVED HAME-FASTENER.

The Schedule referred to in these Letters Patent and making part of the same.

TO ALL WHOM IT MAY CONCERN:

Be it known that I, ALVAH SWEETLAND, of the city of Syracuse, in the county of Onondaga, and State of New York, have invented a new and useful Improved Hame-Fastener; and I do hereby declare that the following is a full, clear, and exact description of the construction and operation of the same, reference being had to the annexed drawings, making a part of this specification, in which—

Figure 1 is a perspective view, and

Figure 2 is a view of each separate part.

Like letters represent like parts.

Letter A represents the eyes; letter B, the strap; letter C, the lever; letters D D D, the bars that form the eyes; letters F F, the slots in the strap and lever.

I construct my hame-fastener of iron or brass, or its substitutes. The eyes are made as represented in the drawings. The lower end of the strap is bent in the form of a hook, and is fastened, and plays into the slot of the lever, and the lever plays in the slot of the strap. The lower end of the lever is formed into a hook, which hooks into the eyes, and then the lever is pressed down on the eyes, and the strap pressed down in the opposite direction, and on the end of the eyes is a hook which fastens into one hame, and on the opposite end of the strap is a hook which fastens in the other hame permanently, and when it is desired to fasten the hames together, when on a horse, the hook on the lever is put in one of the eyes, and then the lever pressed down on the eyes, which locks the fastener, so that it will be impossible for it to be unfastened, only by the hand raising the lever sufficient to loosen the hook out of the eye.

What I claim as my invention, and desire to secure by Letters Patent, is—

The lever C and slot F in the lever, and these parts in combination with each other and the slot of the strap, constructed and operating in the manner and for the purpose substantially as described.

ALVAH SWEETLAND.
